UNITED STATES PATENT OFFICE.

JOHN L. MURPHY, OF SPRINGFIELD, MASSACHUSETTS.

BRIDLE-BIT.

SPECIFICATION forming part of Letters Patent No. 357,497, dated February 8, 1887.

Application filed December 13, 1886. Serial No. 221,351. (No model.)

To all whom it may concern:

Be it known that I, JOHN L. MURPHY, a citizen of the United States, residing at Springfield, in the county of Hampden and State of Massachusetts, have invented new and useful Improvements in Bridle-Bits, of which the following is a specification.

This invention relates to bits for bridles, and is adapted for riding or driving bridles; and the invention consists in the peculiar construction and arrangement of the various parts of the bit, all as hereinafter fully described, and pointed out in the claims.

In the drawings, forming part of this specification, Figure 1 is an end elevation of a bit constructed according to my invention, said figure showing the curb-strap and parts of the head-strap, the driving and curb reins attached to the bit. Fig. 2 is a side elevation 20 of one of the cheek-pieces of the bit, and Fig. 4 is an edge view of the same. Fig. 3 is a side elevation of the mouth-piece with the cheek-pieces removed.

In the drawings, 2 indicates the mouth-piece, 25 having the laterally-curved central portion, B, between its ends, for the usual curbing purpose. The mouth-piece 2 of the bit has a cylindrical journal, a, formed on each end, and to each end of the mouth-piece is suitably secured a crank or curb-rein lever, 3.

In Fig. 1 the lever 3 is shown secured on the end of the mouth-piece 2 by a washer, 20, and a screw, 21, passing through the washer into the end of the mouth-piece. The cheek-pieces 12, one of which is secured on each end 35 of the mouth-piece 2, in the position shown in Fig. 1; is, as shown, of circular form, and consists of the external ring, b, having on one side thereof the loop e, in which is secured the lower 40 end of the head-strap 10, the hollow hub 13, and the arms 14, 15, and 16, which unite said hub to said ring, the arm 15 having therein the slot v, to provide for securing one end of the curb-strap 9 thereto, and the arm 14 has 45 in its under edge the socket c, which receives the stud 4 on the crank-arm 3 when the curb-curve B of the mouth-piece lies in the position shown in Fig. 1, or in such position as occasions no uneasiness or restraint to the horse.

50 In the drawings, each of the arms 3 is shown to be provided with said stud 4; but one

thereof may be omitted, if desired, without impairing the operative efficiency of the bit.

When the parts of the bit are assembled together in operative relation, one of the cheek-pieces 12 is placed on each end of the mouth-piece, the hollow hub 13 extending over and covering the journal a. Said hub is of the same external diameter as that part of the mouth-piece against which the end of the hub 55 abuts, so that the parts of the mouth-piece and hub which come between the teeth of the horse are in the same plane, and the curve B in the mouth-piece is brought under the roof of the horse's mouth, the cheek-pieces serving to 60 prevent any unfeelingwise motion of the latter.

The crank or curb arms 3 are secured, as above described, on the ends of the mouth-piece 2, outside of the cheek-pieces 12, thereby retaining the latter in place on the journals a. 70 The curb-strap 9, which is buckled under the lower jaw of the horse, serves to hold the cheek-pieces in proper position when the mouth-piece is rotated to bring the curve B against the roof of the mouth of the horse to 75 curb him.

The strap 8 represents one end of the driving-rein, which is buckled in such position on the ring of the cheek-pieces that when pulled to guide the horse it does not cause any rolling movement of the mouth-piece 2.

The eyebolts 5 in the cranks or curb-rein levers 3 are provided with rings 6, in which the ends of the curb-rein 7 are secured, as shown.

The mouth-piece 2 has a free rotary motion in the hubs 13 of the cheek-pieces, and in practice the curb-rein 7 is let hang perfectly free, and under these circumstances the curve B in the mouth-piece offers no resistance to 90 prevent the horse from closing his mouth on the hubs 13 and the mouth-piece; but in so closing his mouth the roof thereof is brought against said curve, thereby causing the mouth-piece and the arms 3 to assume the positions 95 shown in Fig. 1, the studs 4 swinging to the end of the recesses e in the arms 14 of the cheek-pieces, thereby limiting the rolling motion of the mouth-piece and holding the end of the arm 3 always below the axis of the latter; but when the horse requires curbing that is effected by drawing on the curb-rein 7, 100

thereby swinging the curve B of the mouth-piece upward against the roof of his mouth and preventing him from shutting it on the bit.

The extension of the hollow hubs 13 inwardly from the sides of the horse's mouth and thus providing bearings, so to speak, for the ends of the mouth-piece to roll or rock in, obviate to a great extent the danger of injury to the mouth when it becomes necessary to curb the horse with much force.

What I claim as my invention is—

1. A bridle-bit consisting of the mouth-piece 2, having the central curve, B, and the journals *a*, combined with the cheek-pieces 12, having 15 hollow hubs thereon to receive said journals, and in which the mouth-piece has a rolling motion, the crank-arms 3, having the studs 4

thereon, secured on the ends of the mouth-piece, and the curb-rein 7, attached to said crank-arms, substantially as set forth. 20

2. In combination, the cheek-pieces 12, each provided with the hollow hub 13, the loop *c*, the slot *v*, and recess *e*, the curved mouth-piece 2, having the journals *a* thereon, the crank-arms having the studs 4 thereon, secured on the ends of the mouth-piece, outside the cheek-pieces, the head-strap 10, the curb-strap 9, and the curb-rein 7, attached to said crank-arms, substantially as set forth. 25
